DESIGN FOR A COMBINED QUOIT AND
HORSESHOE PITCHING DEVICE

Joseph Koches, Warren, Ohio

Application July 9, 1947, Serial No. 140,163

Term of patent 7 years

(Cl. D34—5)

To all whom it may concern:

Be it known that I, Joseph Koches, a citizen of the United States, residing at Warren, in the county of Trumbull and the State of Ohio, have invented a new, original, and ornamental Design for a Combined Quoit and Horseshoe Pitching Device, of which the following is a specification, reference being had to the accompanying drawing, forming a part thereof.

In the drawing:

Figure 1 is a plan view of a combined quoit and horseshoe pitching device, showing my new design,

Figure 2 is an end elevational view of the same,

Figure 3 is a transverse sectional view corresponding generally to the line 3—3 of Figure 1, and

Figure 4 is a small scale perspective view of the device.

I claim:

The ornamental design for a combined quoit and horseshoe pitching device, substantially as shown.

JOSEPH KOCHES.
